UNITED STATES PATENT OFFICE.

LUCIUS T. GIBBS, OF MILWAUKEE, WISCONSIN.

CONTROLLING MECHANISM FOR ELECTRIC MOTORS.

SPECIFICATION forming part of Letters Patent No. 555,503, dated March 3, 1896.

Application filed January 2, 1896. Serial No. 574,020. (No model.)

To all whom it may concern:

Be it known that I, LUCIUS T. GIBBS, of Milwaukee, in the county of Milwaukee and State of Wisconsin, have invented certain new and useful Improvements in Controlling Mechanism for Electric Motors; and I do hereby declare that the following is a full, clear, and exact description of the invention, which will enable others skilled in the art to which it pertains to make and use the same, reference being had to the accompanying drawing, and to the letters of reference marked thereon, which forms a part of this specification.

15 The main object of my invention is to avoid injury to the motor by an abrupt increase of current through the armature, or the sudden closing of the armature-circuit, so as to allow the full current to pass through the armature 20 before it has time to get under motion and generate a counter electromotive force.

It consists of certain novel features in the construction and arrangement of component parts of the controlling devices hereinafter 25 particularly described and pointed out in the claims.

Referring to the drawing, which shows in elevation my improved switch in connection with a shunt-wound electric motor, which 30 with the electric circuits are shown in diagram, A designates the armature and B the fields of an electric motor. C and D are the main wires or conductors by which the motor is supplied with current, and E is a 35 double pole or other suitable switch for manually opening and closing the main circuit.

c e is a branch of the main circuit which passes through the armature and may be designated, for convenience, the "armature-circuit," and d d is a branch of the main circuit which passes through the fields of the motor and may be designated the "field-circuit."

F is a manually-operated switch-lever pivoted upon a pin f in the usual or any suitable way, and g to g' are contacts over which the lever F is adapted to sweep and to engage successively, connected with each other by resistance-coils G G and with the armature 45 circuit c in series.

f' and f'' are stops for limiting the movement of the switch-lever F in its initial and

final positions, as shown by full and dotted lines. In its initial position, as shown by full lines, the circuit through the armature of the 55 motor is broken, and in its final position, as indicated by dotted lines, the armature-circuit is closed and all of the several resistance-coils are cut out of said circuit, so that the full current passes through the armature. 60 As the lever is turned from its initial to its final position, it first engages the contact g, closing the armature-circuit with the several resistance-coils G G included in circuit. As it passes in succession over the several contacts g' to g'', the resistance-coils G G are successively cut out as the armature increases 65 in speed and generates counter electromotive force.

H is a switch-arm made of iron or steel and 70 pivoted on the pin f concentrically with lever F, with which it is in electrical connection, and independently of which it is movable.

K is an electromagnet which has its winding included in the field-circuit d in series 75 with the field and its core k projecting at one end into the path of the arm H, and constituting a contact-stop therefor. The arm H constitutes or carries the armature of said electromagnet and with the lever F serves as 80 a part of the armature-circuit c, the core or pole-piece k of the electromagnet being electrically connected with the main wire or conductor D.

h is a stop arranged to limit the movement 85 of the arm H away from the core of the electromagnet at such a distance therefrom as to be unaffected by the attraction of said magnet when energized by the normal working current.

L is a spiral spring attached at the ends to the lever F and arm H by means of pins or studs I I', which carry it in a position to clear the center pin f when the lever F is turned in either direction past the line of the arm H. 90 The spring L is made of such tension or strength that it will not overcome the attraction of magnet K when it is energized by the normal working current, but, when an interruption or material decrease in said current 100 occurs while the switch-lever F is in its final position, will instantly shift said arm against its back-stop h and break the armature-circuit.

My improved device operates as follows: Assuming the parts of the apparatus to be in the positions shown by full lines in the drawing, to start the motor the main circuit is closed by means of the switch E, thereby closing the branch circuit d through the fields B B of the motor and through the winding of magnet K. The switch-lever F is then turned to the left, and upon engaging the first contact g closes the armature-circuit through all the resistance-coils G G, lever F, arm H and core k of magnet K. The armature now starts slowly, and as its speed increases the lever is moved progressively to the left, cutting out one resistance-coil G after another until it rests in its final position in engagement with contact g⁷, as indicated by dotted lines, and all the resistance-coils are cut out of the armature-circuit and the full current passes without external resistance through the armature. In moving the lever F from its initial to its final position the spring L is carried over and past the center pin f, and in the final position of said lever tends to hold it firmly against the stop f² in engagement with the contact g⁷ and also to pull the arm H away from the core of magnet K; but said magnet, having been energized at the outset by the closing of the main and field circuits through switch E, holds said arm in contact with its core and maintains the armature-circuit as long as the main and field circuits are unbroken, and the current passing through them is not interrupted or materially weakened. If, however, the main circuit or the field-circuit is broken, either accidentally or, as usual, by the operation of the main switch E, the electromagnet K will gradually lose its excitation as the armature of the motor slows down until its attraction is overcome by the tension of spring L, which will thereupon instantly snap it over against the stop h and break the armature-circuit. If now the main switch E be closed again while the switch-lever F is in its final position, the motor will not start, because the armature-circuit is broken between the pole of magnet K and arm H and the attraction of said magnet is not sufficient to restore said arm to its original position against the tension of spring L. To start the motor again under these conditions, it is necessary to turn the switch-lever F back to its initial position against stop f² or till it passes the line of arm H, whereupon the spring L, passing to the opposite side of the center of pin f, will snap the arm H against the pole-piece k of magnet K, where it will be held by the attraction of said magnet if the switch E is closed and the field-circuit is supplied with the normal working current. The motor can now be started in the manner hereinbefore explained by turning the switch-lever F to the left, which first closes the armature-circuit with all the resistance included therein and gradually cuts out such resistance until said lever reaches its final

position in engagement with the last contact g⁷. By this means and in the manner above explained it is impossible to pass the full normal current through the armature-circuit 70 at once before the armature has had time to get in motion and generate a counter electro-motive force that will prevent injury thereto by the full or normal current.

The switch-lever F may be stopped in its 75 initial position on the first contact g without breaking the armature-circuit. This is sometimes desirable and does not affect the operation of the automatic switch-arm H, as hereinbefore described.

I have shown and explained my improvements in connection with a shunt-wound motor in which the magnet K is preferably placed in the field-circuit d, as shown; but they are also applicable to a series-wound motor 85 in which the fields and armature of the motor and the winding of said magnet would be arranged in series with each other.

Under certain conditions the series of resistances in the armature may be dispensed 90 with and still the automatic switch-arm employed to advantage in connection with a manually-operated switch-lever, such as F, for opening and closing the armature-circuit.

I claim—

1. In controlling mechanism for electric motors, the combination with a lever adapted to gradually cut out of the armature-circuit a series of resistances in starting the motor, of an automatic safety-switch comprising an 100 arm electrically connected with said lever, and movable independently thereof, an electromagnet having its winding in series with the field of the motor and its core or pole-piece projecting into the path of said arm, 105 and in electrical connection with the armature-circuit, and a spring arranged to pull said arm out of contact with said pole-piece when said magnet is de-energized and the switch-lever is in its final position, substantially 110 as and for the purposes set forth.

2. In controlling mechanism for electric motors, the combination with a series of contacts and resistances connected with one of the main conductors of the motor and a switch-lever arranged to sweep over said contacts, of an arm electrically connected with said lever and movable independently thereof, an electromagnet having its winding in series with the field of the motor and its core projecting into the path of said arm and electrically connected with the other main conductor of the motor, and a spring connecting said lever and arm and arranged to pull the arm away from the core of the magnet when 120 the lever is in its final position, and to pull it toward said core when the lever is in its initial position, substantially as and for the purposes set forth.

3. In controlling mechanism for electric 130 motors, the combination of a switch-lever controlling resistances in the armature-circuit, of

- an automatic safety-switch consisting of an arm pivoted concentrically with said lever and electrically connected therewith, an electromagnet having its winding in the field-circuit of the motor and its pole projecting into the path of said switch-arm and included in the armature-circuit, and a spring tending to pull said switch-arm away from said magnet-pole when the motor is in operation, substantially as and for the purposes set forth.
5. In controlling mechanism for electric motors, the combination with a switch-lever, and a series of contacts and resistances for gradually starting the motor, of an independently-movable switch-arm controlling the armature-circuit; an electromagnet arranged to hold said arm in position to maintain said circuit while the normal current passes through the field, and a spring connecting said arm 15 and lever and tending to draw them together when one is turned out of line with the other in either direction, substantially as and for the purposes set forth.
4. In controlling mechanism for electric motors, the combination with a switch-lever, and a series of contacts and resistances for gradually starting the motor, of an independently-movable switch-arm controlling the armature-circuit; an electromagnet arranged to hold said arm in position to maintain said circuit while the normal current passes through the field, and a spring connecting said arm 20 and lever so as to draw the arm toward the magnet when the switch-lever is in its initial position, and away from it when said switch-lever is in its final position, substantially as and for the purposes set forth.
15. In controlling mechanism for electric motors, the combination of a manual switch-lever controlling resistances in the armature-circuit, a concentrically-pivoted switch-arm controlling the armature-circuit, stops for limiting the movement of said switch and 25 arm, a spring connecting said switch and arm and tending to draw them together when the lever is turned in either direction out of line with the arm, and an electromagnet arranged to hold said arm against the tension of said 30 spring, in position to maintain the armature-circuit while the normal current passes

through the field, substantially as and for the purposes set forth.

6. In controlling mechanism for electric motors, the combination with a switch-lever 40 for manually controlling the armature-circuit, of an independently-movable switch-arm having its winding connected with the motor-circuit, and arranged when energized to hold said arm in position to maintain the 45 circuit, and a spring connecting said arm and lever so as to draw the arm toward the magnet when the switch-lever is in its initial position, and away from it when said switch-lever is in its final position, substantially as 50 and for the purposes set forth.

7. In controlling mechanism for electric motors, the combination with a switch-lever for successively cutting in and out a series 55 of resistances in circuit with the armature of an independently-movable switch-arm controlling the motor-circuit, an electromagnet having its winding in circuit with the motor and arranged when energized to hold said arm 60 in position to maintain circuit for the motor, and a spring connecting said arm and lever so as to pull the arm toward the magnet when the lever is in its initial position, and away from it when said lever is in its final position, substantially as and for the purposes set forth. 65

In testimony that I claim the foregoing as my own I affix my signature in presence of two witnesses.
